METHODS OF MANUFACTURING EVACUATED AND GAS-FILLED DEVICES

Vincent J. De Santis, Robert E. Manfredi, and Henry J. Nolte, Schenectady, N.Y., assignors to General Electric Company, a corporation of New York

Application December 28, 1956, Serial No. 631,321

16 Claims. (Cl. 316—25)

The present invention relates generally to evacuated and gas-filled devices and pertains more particularly to new and improved methods of manufacturing same.

In various arts such, for example, as the electric discharge device, electric switch, electric lamp, and vacuum-insulated container arts, devices are often manufactured which are either evacuated of their gaseous contents to a high degree or are evacuated of the normal atmosphere and subsequently charged or filled to a predetermined degree with a particular atmosphere. Heretofore, the evacuation required for both types of devices generally has been accomplished by mechanically exhausting or pumping down the gaseous contents thereof. In accordance with some prior art methods the required degree of exhaust has been obtained solely by the utilization of mechanical exhaust equipment which for the present discussion is considered to include pumps of the oil sealed and vapor-diffusion types. With other methods, and particularly in the electric discharge device and lamp arts, the devices have been first mechanically exhausted and then undesirable residual gases have been chemically sorbed by means of the well-known gettering processes. Most of these methods involve the necessity of mechanical exhaust equipment, the provision of exhaust tubulations or vacuum connections on the devices, and require the step of pinching-off or sealing such tubulations following exhaust and in a manner which will not adversely affect the previously attained vacuum. From the standpoints of economy, quality, facility and time of processing and simplification of construction of the devices, it is desirable to provide methods whereby enveloped devices may be satisfactorily exhausted to substantially any desired degree of evacuation without the use of mechanical exhaust equipment, without the provision of exhaust tubulations on the devices and without the tubulation pinch-off step.

Additionally, in the various arts mentioned, and particularly the electric discharge device art, it is generally the practice to bake-out, or evolve through heating, and to exhaust gases ordinarily occluded in the materials of the components of the devices, in order that such gases cannot subsequently deleteriously affect a vacuum or gas charge obtained therein.

Furthermore, often such devices are manufactured to include cathode structures comprising materials which, in order to be rendered active for emission, must be chemically reduced. This is generally accomplished by energizing the cathodes substantially above normal operating temperatures following the aforementioned bake-out step.

A heating step is also often required to complete the envelope structure of the device, as by brazing together the various parts comprising the structure, such for example, as insulative wall sections and metallic terminal members.

From the preceding discussion it will be appreciated that the ordinary processing of devices generally involves a plurality of separate heating steps to accomplish bake-

2

out, cathode activation and sealing, and such procedure has been found both costly and time consuming.

As regards the manufacture of gas-filled devices which previously have been evacuated in preparation for receiving gas charges, such, for example, as hydrogen thyratrons or inert-gas discharge tubes or switches, there is generally encountered a problem in avoiding admission of undesirable gases during charging. Additionally, in manufacturing some gas-filled devices, there is often encountered the further problem of maintaining the filling within a desired pressure range required for normal, prolonged, efficient operation. Thus, it is desirable to provide means and methods for facilitating the charging of gas-filled devices as well as maintaining the filling at desired operating pressures during the normal life of the device.

Accordingly, the primary object of the present invention is to provide new and improved methods of manufacturing evacuated devices.

Another object of the present invention is to provide a new and improved method of evolving occluded gases from an envelope and its contents and sealing and evacuating the envelope by means of a single heating step and without any heretofore-required exhaust tubulation or mechanical exhaust equipment.

Another object of the present invention is to provide a new and improved hydrogen furnace process whereby an envelope structure comprising multiple parts may be brazed, sealed and permanently evacuated to a high degree.

Another object of the present invention is to provide a new and improved method of manufacturing an electric discharge device whereby chemical constituents thereof requiring reduction to be effective may be reduced in conjunction with the evacuation of the device and as a result of a single heating step.

Another object of the present invention is to provide new and improved methods of gas charging an envelope.

Still another object of the present invention is to provide new and improved methods of manufacturing evacuated and gas-filled devices whereby substantial economies in manufacturing effort, time and materials and improved quality are realized.

Further objects and advantages of the present invention will become apparent as the following description proceeds and the features of novelty which characterize the invention will be pointed out with particularity in the claims annexed to and forming part of the specification.

In carrying out the objects of the present invention an envelope is heated to a predetermined elevated temperature range in an open condition in a predetermined atmosphere whereby the normal gaseous contents of the envelope are substantially displaced by a thermally expanded quantity of the predetermined atmosphere. Heated in the envelope while it is open is a quantity of substance capable of sorbing a substantial quantity of the predetermined atmosphere in the predetermined elevated temperature range and at relatively reduced temperatures. The envelope is sealed while in the mentioned predetermined elevated range and then the envelope and its contents are permitted to cool. Thus, the internal pressure of the envelope can be effectively reduced. The envelope can comprise multiple parts adapted for being joined as by brazing to complete the envelope and the envelope can be adapted for being sealed thermally; and both the brazing and sealing can comprise the same step and can be effected by the same heating step as that utilized to raise the temperature of the gas-sorbing material in the envelope. Thus, brazing, sealing and evacuation can be effected in a single step, resulting in a substantial reduction in manufacturing expense and time. Additionally, the same heating step can be utilized

to effect out-gassing of the material in the envelope and its contents, and can be further employed to reduce chemically any of the material in the enveloped device that requires reductions for desired operation.

For a better understanding of the invention reference may be had to the accompanying drawing in which:

Figure 1 is a schematic illustration showing both a device constructed in accordance with an embodiment of the invention, and processing equipment that may be utilized in carrying out the method of the present invention;

Figure 2 is an enlarged fragmentary perspective illustration of a portion of an enveloped device sealed and evacuated in accordance with the method of the present invention, and with the equipment illustrated in Fig. 1.

Figure 3 is a charge illustrative of the effects of some of the materials, quantities thereof and operating temperatures employed in the method of the present invention; and

Figure 4 is an enlarged sectional illustration of an enveloped device sealed and charged with hydrogen in accordance with a modified form of the present invention.

Referring to Figure 1, there is shown a furnace, generally designated 1, of a type in which the method of the present invention may be advantageously carried out. The furnace 1 is elongated and comprises a pre-heat zone 2, an intermediate zone 3 and a cool-down zone 4. The zone 3 is adapted for being directly and concentratedly heated as by a suitably arranged and adjustably controllable electrical heating arrangement generally designated 5. The opposite ends of the furnace comprising the pre-heat and cool-down zones are heated indirectly by the arrangement 5. The end walls of the furnace may comprise access doors 6, provided for permitting the placing of objects to be processed into the pre-heat zone 2 and removing same from the cool-down zone 4.

Provided on the floor or bottom wall of the furnace is a pair of spaced rails 10 on which objects can be moved through the furnace. Movement of the objects on the rails and through the various zones of the furnace may be effected by operation of a push rod generally designated 11, slideably arranged in and operable through the access door 6 in the right-hand side of the furnace in Figure 1. It will be understood that any suitable conveying means can be employed, such for example, as a chain drive, for moving objects through the furnace.

Gas inlets 12, including means for selectively adjusting the gas flow therethrough, are provided in the wall of the furnace on either side of the heating arrangement 5 and an outlet 13 is provided in the lower portion of each of the doors 6. Except for the mentioned inlets and outlets, the furnace is adapted for being closed during operation.

For purposes of explanation the present invention is illustrated and hereinafter will be described principally with reference to the manufacture of electric discharge devices. This is desirable inasmuch as evacuated electric discharge devices generally require a high degree of evacuation and removal of substantially all active gases in order to avoid contamination of the usual electrode elements contained in these devices. Thus, the evacuation capabilities of the present invention will be more strikingly presented. Also, gas-filled electric discharge devices represents a good example of the types of enveloped devices that can be gas charged by means of the present invention. However, from the outset it is to be understood that the invention is not limited in application to electric discharge devices but is applicable to the manufacture of numerous other types of envelopes and enveloped devices adapted for being evacuated to some extent or gas-charged with a particular atmosphere.

Illustrated in Figure 1 as being disposed in the pre-heat zone 2 of the furnace and on the rails 10 therein is a stacked arrangement of elements which are adapted

for being bonded together, as by brazing or soldering, to provide an electric discharge device hereinafter generally designated 15 and comprising an envelope 16, an anode 17, a cathode structure 18 and a grid structure 19.

The anode 17 can comprise the planar bottom portion of a cup-like member 20. The member 20 is adapted for comprising the upper end of the envelope 15 and is provided with a rim 21 formed with a downturned lip 22. The lip 22 is adapted for surrounding and being bonded, as by brazing, to the outer peripheral surface of the upper end of a high-refractory insulative sleeve 23 adapted for comprising part of the side wall of the envelope 16. The sleeve 23 may be formed of any suitable ceramic material such, for example, as alumina or magnesium silicate and may be metallized in the brazing areas according to the method disclosed in United States Letters Patent 2,667,432, issued January 26, 1954 to Henry J. Nolte and assigned to the same assignee as the present invention.

Seated between the rim 21 of the anode member 20 and the upper end of the sleeve 23 and adapted for effecting a metallic bond therebetween in a manner to be described in detail hereinafter is a washer 24 formed of any suitable solder material. Associated with the lower end of the insulative sleeve 23 and reentrant in the sleeve 23 is a substantially frusto-conical conductive grid-support member 25. As illustrated in Figures 1 and 2, the aforementioned grid structure 19 may comprise a planar array of grid wires 26 supported in a substantially parallel spaced relation to the anode 17 on the inner end of the support member 25 extending into the sleeve 23. As best illustrated in Figure 2 the support member 25 is formed to include a rim 27 having an upturned lip 28 adapted for surrounding and being bonded, as by brazing, to the upper peripheral surface of the lower end of the sleeve 23. Seated between the rim 27 and the lower end of the sleeve 23 is a solder washer identical in construction and purpose to the washer 24. These and other identical washers will hereinafter be referred to simply as washers 24.

Provided for being bonded to the lower side of the rim 27 of the grid support member is a conductive sealing ring 30 including a downturned lip 31 adapted for surrounding and being bonded, as by brazing also, to the outer peripheral surface of an upper end of a second insulative sleeve 32. The sleeve 32 can be formed of the same material as the sleeve 23 and is also adapted for comprising part of the side wall of the envelope 16. Disposed between the ring 30 and the upper end of the sleeve 32 is one of the aforementioned solder washers 24.

Disposed between the rim 27 of the grid-support member 25 and the sealing ring 30 is a solder washer 33 which can be formed of the same material as the washers 24. However, as seen in Figure 2, the washer 33 is formed with radial corrugations, providing a plurality of substantially large passages affording communication between the interior and exterior of the envelope 16. Before brazing occurs the envelope assembly is open in the sense that gas can pass into and out of the assembly at all the solder washers and between the various sections of the assembly. However, it will be seen that the washer 33 is effective for holding the upper and lower sections of the envelope structure apart a substantial amount and thus affords greater gas flow between the sections of the envelope. The washer 33 is effective in this manner until the washer melts, and the purpose for providing such communication will be brought out in detail hereinafter.

Associated with the lower end of the sleeve 32 is a tubular conductive cathode-support member 34. The cathode-support member 34 is similar to the grid-support member 25 and is formed with a rim 35 having an upturned lip 36 adapted for surrounding and being bonded, as by brazing, to the outer peripheral surface portion of the lower end of the sleeve 32. Disposed between the

rim 35 and the lower end of the sleeve 32 is one of the above-mentioned solder washers 24. A conductive sealing ring 37, identical to the ring 30 and including a down-turned lip 38, is provided for being brazed to the rim 35 of the cathode support member 34 through the use of a washer of the type including the radial corrugations and designated 33 in Figure 2. The ring 37 is adapted also for being brazed to the upper end of a third ceramic sleeve 40 through the use of a washer 24. The sleeve 40 can be identical to the sleeve 32.

The cathode-support member 35 includes a substantially frusto-conical conductive portion re-entrant in the sleeve 32 and having the cathode structure 18 suitably, conductively mounted thereon. The cathode structure 18 can comprise a container or sleeve 42 supporting an electron emissive disk 43 in predetermined spaced relation with the wires of the grid 19. The disk 43 can be formed of the conventional carbonate materials adapted for being emissive following activation or reduction thereof to oxides upon heating to a predetermined substantially elevated temperature. A filamentary heater 44 is contained in the sleeve and one side thereof can be suitably electrically connected to the cathode-support member 34. Provided at the lower end of the sleeve 40 is a conductive, inverted, cup-like member 45 adapted for closing the lower end of the envelope 16. The member 45 is formed with a rim 46 and an upturned lip portion 47, and a washer 24 is provided between the rim 46 and the lower end of the sleeve 40 for effecting a braze therebetween. The member 45 has the other end of the filamentary heater 44 suitably electrically connected thereto.

As will be clear from the drawing, the lip portions of the various electrode support elements and sealing rings are adapted for serving as external electrical contact surfaces on the device and, accordingly, these members can be advantageously formed of copper or clad chrome iron.

Provided in the envelope 16 in the form of a disc 50 and adapted for use in effecting evacuation of the envelope by sorption, in a manner to be described in detail hereinafter, is a predetermined quantity of elemental titanium. The quantity of the titanium used is dependent upon the internal volume of the envelope 16, temperature employed and other factors which will be understood from a detailed example appearing hereinafter. Additionally, as regards the effects of the material of the disc 50, the term "sorption" will hereinafter be employed to refer generically to the phenomena of absorption and adsorption and the term "desorption" will be used in reference to the reverse processes.

The disc 50 is supported on the internal surface of the member 45 and, in order to avoid undesirable alloying of the titanium with the material of the member 45 an interposed layer of molybdenum 51 is provided. This arrangement, is also adapted for facilitating detection of leaks in a manner to be described hereinafter. As shown in the drawing, titanium 50 and the molybdenum layer 51 may be centrally apertured, thus to provide for direct connection of one of the heater leads to the member 45.

Following stacking of the various elements comprising the device 15 in the manner described above and illustrated in Figure 1, the stacked arrangement is placed in the pre-heat zone 2 of the furnace 1. The furnace 1 is continuously supplied through the inlets 12 with dry hydrogen and the excess furnace atmosphere is permitted to escape from the furnace through the outlets 13 in the ends of the furnace. The supply of hydrogen and escape thereof is such that the atmosphere of the furnace is continuously being replenished by dry hydrogen and any other gases in the furnace are flushed out through the outlets 13. Additionally, in the furnace the hydrogen is heated and thereby substantially expanded or rarefied. The advantage of this will be brought out in detail hereinafter.

In the pre-heat zone 2 the cathode disc 43 can be

activated, or chemically reduced from carbonates to oxides, by completing a circuit through the filamentary heater 44 and a power source generally indicated at 52. A pair of electrical contacts 53 are provided in the furnace structure to facilitate contact with the cathode terminals comprising the upturned lips 36 of the cathode-support member 34 and the rim 46 of the member 45. In this manner, the cathode filament or heater can be energized sufficiently to reduce the carbonate material 10 of the disc 43 for thus rendering the disc satisfactorily emissive at contemplated normal operating temperatures.

Also, while the device 15 is in the pre-heat zone 2 it is heated sufficiently to commence a bake-out operation or the evolution of undesirable occluded gases in 15 the material of the device, such for example as oxygen, water vapor, nitrogen, carbon dioxide and carbon monoxide.

The device 15 is transported on the rails 10 to the heating zone 3, as by manipulation of the pusher 11, and the heating arrangement 5 is energized to elevate the temperature of the device substantially, thus to complete the bake-out step. Normally the material of the disc 50 includes an oxide coating resulting from exposure to the normal atmosphere. During elevation of the temperature of the device in the heating zone this coating is disposed of, after which the titanium first sorbs hydrogen and then desorbs substantially all the hydrogen it had previously sorbed. The desorbed hydrogen expands outwardly of the device through the communicative openings or passages between the interior and exterior of the envelope afforded by the corrugations of the washers 33 as well as spaces between the envelope sections and the solder washers 24 until there occurs 35 a substantial equilibrium of pressure between the atmosphere in the device and that in the furnace. Additionally, the passages afforded by the washers enable the atmosphere of the furnace and the gaseous contents of the device, including the normal atmospheric constituents, the residual gases resulting from activation of the cathode and out-gassing of the materials of the device, to admix. Due to the above-described continuous replenishment of the dry hydrogen atmosphere in the furnace and the flushing effect afforded thereby, the 40 admixing of the gaseous contents of the envelope and furnace atmosphere results in such gaseous contents of the envelope being flushed out and substantially displaced by an essentially pure hydrogen atmosphere corresponding to the expanded or rarefied atmosphere of the furnace. At a predetermined elevated temperature the 45 solder washers 24 and 33 flow, thus to seal the device and entrapping in the envelope a residual quantity of the mentioned expanded or rarefied essentially pure hydrogen atmosphere.

It will be understood from the foregoing that the present invention is not limited to the use of the corrugated washers 33 to provide substantial communicative passages between the interior and exterior of the envelope structure or, in other words, to hold the envelope open 60 to a degree which will facilitate the flushing step. Various alternative methods can be employed. For example, a mechanical fixture operable from the exterior of the furnace can be employed for gripping one or more of the sections of the envelope and holding same in a 65 raised position relative to an adjacent lower section carrying a solder washer such as 24. Thus, the envelope can be held widely open during the time required for flushing the structure and until the material of the solder washer 24 melts. Subsequently, the raising fixture can 70 be released to lower the upper section upon the lower section to effect sealing of the device. The operation of the fixture can be temperature responsive and thus, when used in conjunction with a solder washer 24 can accomplish the same effect as the washers 33.

The titanium comprising the disc 50 is adapted for

sorbing substantial quantities of hydrogen at relatively low temperatures and releasing or desorbing hydrogen at elevated temperatures, or in other words, the titanium reacts reversibly with hydrogen. This phenomenon is explained in detail in chapter 9 of the text entitled, "Vacuum Techniques," written by Saul Dushman and published by John Wiley and Sons. Additionally, at the elevated temperatures at which the titanium 50 releases hydrogen, it is further effective for irreversibly sorbing or reacting with active gases other than hydrogen. The compounds thus formed with these other active gases are stable and, therefore, there is no disassociation when the material assumes relatively low temperatures.

Where it is desired to use corrugated solder washers to hold the envelope open these washers, as well as all other solder washers, are formed preferably of a solder material that will flow and seal or close the envelope of the device in a temperature range in which the titanium has released or desorbed substantially all previously sorbed hydrogen and in which it is adapted for sorbing substantially all of the residual active gases other than hydrogen in the envelope. This temperature range is substantially wide and sorption of the residual active gases other than hydrogen continues for a substantial time after the solder material has melted. Thus, when the temperature is reduced toward the lower side of the range in which the sealing occurs substantially all of the active gases other than hydrogen will have already been sorbed by the titanium and only the residual hydrogen and any residual inert gases will remain in the device. Additionally, at this stage of the process the titanium is in almost its pure elemental state and the previous heating thereof has effected a lattice change in the structure of the material which makes it more solvent or more highly sorbing of the residual hydrogen upon cooling. Thus, the next step of the process involves reducing the temperature of the device, including the titanium therein, as by first transporting the device into the cool-down zone 4 of the furnace and then removing it completely from the furnace. In this manner, the solder material is solidified to form the seals 54 shown in the left-hand side of Figure 1. Additionally, as the temperature of the device, and therefore, the titanium disc 50 decreases, the titanium voraciously sorbs the residual hydrogen or reacts therewith to form a subtitanium hydride, or a solid solution of hydrogen in titanium, and thus the device is evacuated substantially to a high degree. Any residual inert gases are ordinarily in small and negligible quantities such, for example, as below 10^{-10} mg. of mercury and for most practical purposes are not found deleterious to operation of the evacuated device.

Inasmuch as titanium hydride is a granular substance and is generally undesirable in an uncontained form in a device such as 15, the member 50 is formed of sufficient material to insure that it will not be completely converted to titanium hydride upon sorption of the entrapped hydrogen. That is, after the member 50 has served its purpose in evacuating the device, it will normally comprise a uniform solid solution of hydrogen in titanium and will still constitute a unitary element. Additionally, the member 50, after serving to evacuate the device, is adapted for serving as what might be termed as a "built-in leak detector." That is, if any of the seals 54 is defective leakage into the device of atmospheric hydrogen will ultimately convert the member 50 to granular titanium hydride which upon shaking of the device, will cause a rattling noise, signifying a leak.

The final pressure obtained in the sealed device 15 can be viewed as a function of the internal volume of the device, the amount of material used in forming the member 50, and the operating temperature of the device inasmuch as temperature increases will tend to release previously sorbed hydrogen from the member 50. The critical or minimum amount of material to be used in the member 50 for obtaining a vacuum in the device

5 can be defined as the stoichiometric equivalent of the quantity of gases in the tube at the time of sealing. However in order to insure a desired high vacuum, to avoid conversion of the material to an undesirable granular state, and to minimize operating-temperature effects on the internal pressure of the device, it has been found desirable to form the member 50 of a quantity of material approximately two to three times the amount considered to be critical.

10 The member 50 is located remote from the cathode in the device in order to avoid any substantial heating of the member 50 during normal operation of the tube which would have the tendency of releasing previously sorbed hydrogen.

15 In order that the just-described process may be more readily practiced a detailed example including quantities, temperature ranges and times for performing the various steps of the process is provided herebelow:

Example A

20 In an enveloped device of the type designated 15 in the drawing and having an internal volume of approximately 69 cc., the titanium disc 50 can be formed of approximately 148 mg. of titanium. Additionally, the 25 solder comprising the washers 24 and 33 can be silver solder adapted for melting and flowing into the joints between the various elements at approximately 778° C. which, as seen in Figure 3, is beyond the inflection point on the titanium curve. Alternatively and in place of the 30 corrugated solder washer a flat solder washer can be used in conjunction with any suitable means adapted for holding a section of the envelope in a raised position and operable for lowering the raised section onto the molten solder thereby to seal or close the envelope at approximately 778° C. The furnace 1 is heated by means of the arrangement 3 and is supplied with dry hydrogen. The device 15 is placed initially in the pre-heat zone 2 wherein flushing out or displacement of the normal gaseous contents thereof by the hydrogen atmosphere of the furnace commences. Additionally in the pre-heat zone of the furnace the cathode 43 is activated by completing the circuit of the filamentary heater 44 through the power source 52 and thus raising the temperature of the cathode to approximately 1000° C. This temperature is maintained preferable for approximately 12 minutes. Thus, the carbonates of which the cathode material is formed are reduced to oxides and rendered partially active or emissive. This reduction and activation step also results in carbon-monoxide, carbon-dioxide and other gases being released in the envelope. These gases are also flushed out of the envelope or displaced by the continuously replenished hydrogen atmosphere of the furnace.

35 Also, while in the pre-heat zone the material of which the device is constructed heats up and evolves occluded gases, thus to commence the out-gassing of the process. The gases thus evolved are also flushed out by the hydrogen.

40 Subsequently, the device is transported on the rails 10, as by operation of the pusher 11, into the heating zone 3. In this zone, and by continuous energization of the furnace heating arrangement 5, the temperature of the device and its constituent parts is raised and maintained for approximately 10 minutes in a range between approximately 778° C. and 1000° C. In approaching this temperature range the oxide coating normally present on the titanium is decomposed and the titanium 45 first sorbs hydrogen from the hydrogen atmosphere now present in the envelope, which sorption generally occurs between approximately 25° C. and 400° C. Then as the temperature more closely approaches 778° C. the titanium desorbs the previously sorbed hydrogen, thus manifesting its reversible reactive nature in respect to hydrogen. In the mentioned range, substantially all of the hydrogen 50 previously sorbed by the titanium is released and sub-

stantially all of the gases normally occluded in the materials of the device are baked-out and displaced by hydrogen from the furnace atmosphere. Additionally in this range, after approximately 2 or 3 minutes therein, the solder material melts, the washers 33 collapse and the envelope is thereby sealed. The resultant seals remain in a molten state but are effective for entrapping in the envelope an essentially hydrogen atmosphere. Still further, in the mentioned range, and throughout the remaining time therein, the titanium is effective for permanently or irreversibly combining with any active gases in the envelope, other than hydrogen, which had not been displaced by hydrogen from the furnace atmosphere or which were evolved from the materials of the device subsequent to sealing of the envelope. It is to be recognized that the bake-out process continues as long as the device is maintained in the elevated temperature range and the titanium will continue to be effective in sorbing evolved gases for an extended period even after sealing of the device occurs, or in other words for as long as the bake-out results in evolution of gases and as long as the titanium stands at a temperature whereat it will combine with such gases.

Following the above-described ten minute period of heating in the zone 3, the device is pushed into the cool-down zone 4 wherein the previously molten solder seals solidify sufficiently to braze together the various parts comprising the envelope and to complete the thermal sealing of the envelope.

Subsequently, as the temperature of the device further decreases in the zone 4 and during the cooling of the titanium thus effected, and specifically in the range between approximately 25° C. and 400° C. the titanium relatively rapidly sorbs substantially all of the residual hydrogen in the device. The 148 mg. of titanium is preferably more than is required to sorb all the hydrogen in an enveloped device having the volume of the device 15. Thus, upon cooling to room temperature the titanium sorbs all of the hydrogen and without converting completely to a granular hydride, leaving the device evacuated to a high degree.

By following the steps of the method described in Example A, it has been possible to construct electrical discharge devices evacuated to pressures in the order of magnitude of 1×10^{-7} mm. Hg and having normal electrical operating characteristics. Of course, the amount of titanium used is also proportional to the internal volume of the device evacuated and the amount of titanium employed may be increased or decreased in accordance as the internal volume of the device is increased or decreased, respectively, and in accordance with the degree of evacuation desired.

It will be understood from the foregoing and Figure 3 of the drawing, that the present invention is not limited to the use of titanium. Titanium has been described in the detailed example given above in view of the fact that its use has not been found objectionable in electric discharge devices, where it is important that no substance be introduced into the device which would have adverse effects on the electrodes therein and thus on the electrical operation of the device. It will be further understood that titanium hydride is equally employable in the present method inasmuch as it will, upon heating, be reduced to titanium and hydrogen, which resultant titanium will operate in the same manner as that described above. Of course, titanium hydride is granular and for some applications it will be necessary or desirous to provide some form of gas-permeable containing means therefor.

Zirconium is another material which upon heating reacts reversibly with hydrogen and irreversibly with other active gases and has been found suitable for use where the method of the present invention is applied to the evacuation of electric discharge devices. Where zirconium

is used in place of titanium the method of the present invention may be practiced as follows:

Example B

In an enveloped device such as 15 of the drawing and having the same approximate internal volume of 69 cc. the disk 50 can be formed of approximately 282 mg. of zirconium, which is the atomic weight equivalent of 148 mg. of titanium. Thereafter the device 15 can be processed through the hydrogen furnace in the same manner described above with regard to Example A wherein titanium was employed, except that preferably the washers 24 and 33 are formed of a higher-melting-point solder so that sealing of the device will occur at a higher temperature and beyond the inflection point on the zirconium curve, as illustrated in Figure 3. For example, the washers 24 and 33 can be formed of a solder adapted for flowing in a temperature range of approximately 1000° C. and 1150° C. and solidifying at approximately 1000° C. Thus, following activation of the cathode in the pre-heat zone 2 of the furnace in the above-described manner and following a period of heating in the pre-heat zone to initiate bake-out, the device can be moved into the heating zone 3 wherein it is elevated in temperature, by suitable energization of the heating arrangement 5 to the above-mentioned range of approximately 1000° C. to 1150° C. Commencing from the time the device is first placed in the furnace the hydrogen atmosphere of the furnace operates toward completely flushing out or displacing the original gaseous contents of the device as well as other gases resulting from cathode activation and bake-out. When the above-mentioned temperature is attained the washer material becomes molten to effect sealing of the envelope and entrapment therein of a substantially pure hydrogen atmosphere.

If it is desired to employ means other than the corrugated washers to hold the envelope widely open during the hydrogen-flushing step of the process, such other means can be arranged to effect closure or sealing of the envelope at the same temperature at which the corrugations of the solder washer would collapse to effect sealing.

During heating of the device to the above-mentioned temperature range, first, the normal oxide coating of the zirconium will decompose and the elemental zirconium will commence sorbing hydrogen from the furnace atmosphere. Thereafter and at a higher temperature this reaction will reverse and the zirconium will desorb hydrogen leaving the zirconium in a lattice condition conducive to substantial and ready sorption of or combination with active gases, other than hydrogen, at elevated temperatures and with hydrogen upon a subsequent decrease in temperature.

The device is held at the mentioned temperature range for approximately ten minutes during which the above-mentioned out-gassing continues and the zirconium continuously and irreversibly reacts or combines with any evolved active gases other than hydrogen in the device.

Following the ten minute heating period the device is transported to the cool-down zone 4 wherein the temperature decreases and moves through the lower side of the mentioned range whereat the previously melted solder material is solidified for thus joining the various elements comprising the envelope 16 and completing the sealing and entrapment therein of the above-mentioned rarefied hydrogen atmosphere.

Subsequently the device is removed completely from the furnace and the zirconium cools through a range wherein it reacts substantially with, and thus sorbs, the residual hydrogen, thereby to effect a high degree of evacuation of the device. This method of obtaining a vacuum is facilitated by the fact that the hydrogen which was heated and therefore substantially expanded or rarefied when sealed or entrapped in the device is relatively small in quantity at the reduced temperature and the above-mentioned further fact that the previous heating

of the zirconium has left it in a lattice condition highly conducive to gas sorption.

It will be understood that in this example also the amount of zirconium employed is proportional to the internal volume of the device to be evacuated and that it may be varied proportionally in accordance with variations in volume of the device. It will be further understood from the foregoing and Figure 3, that if desirable a suitably contained quantity of zirconium hydride can be employed in place of a member of elemental zirconium.

Additionally, while the step of cathode activation has been described above as effected by energization of the cathode heater, it is to be understood that, if desired, cathode activation can be effected by means of the same furnace heating step that is employed to melt the solder, etc. When activation is accomplished in this manner it is generally desirable to use a higher-melting solder.

It will be understood from the foregoing that the described hydrogen-furnace is not limited to the use of titanium and zirconium and the hydrides thereof nor to the evacuation of electric discharge devices. Instead, this method broadly contemplates a method of highly evacuating and sealing in a single operation any enveloped device or container and the use in such method of any material or alloy of materials selected from the group of materials which are reversibly reactive with hydrogen and are highly sorbing of hydrogen at reduced temperatures. This group not only includes titanium and zirconium and the hydrides thereof but, as shown in Figure 3, also includes cerium, thorium, vanadium and tantalum and the hydrides of each of these elements. Further included in this group, but having no representative curves on the chart of Figure 3 since such would congest the lower portion of the chart and subtract from its clarity, are lanthanum, hafnium, palladium, columbium, neodymium and praseodymium and the hydrides thereof.

Alloys of the above-noted materials are employable where it is desired to obtain the various reactions with the various gases over a wider range than is possible with a single material. For example, an alloy comprising approximately fifty percent of titanium and 50 percent of zirconium has been satisfactorily employed in the above-described process and has been effective for reacting with the various active gases over a wider temperature range and at higher rates of gas sorption than generally obtainable with either titanium or zirconium alone. Additionally, instead of alloying these materials, individual quantities thereof can be used combinationally.

A quantity of any one of the above-mentioned materials having an atomic weight equivalent of the 148 mg. of titanium mentioned in Example A will be operative in the present method for evacuating any enveloped device having an internal volume of approximately 69 cc.; and, of course, this quantity can be varied proportionately in accordance with variations in size of the device.

Each of the above-grouped materials has different characteristics and is either more or less suited for use in evacuating particular enveloped devices or containers in accordance with the method of the present invention. For example, these materials react with hydrogen and the various other active gaseous elements at different temperatures and rates. Thus, some of these hydride-forming materials are more desirable than others for use with particular solder materials and where the duration of the heating step is necessarily or desirably limited. Additionally, even though such materials are all reversibly reactive with hydrogen and adapted for substantial hydrogen sorption at reduced temperatures and, thus, adapted for use in the present invention as broadly contemplated, for given amounts some materials are more sorbing. Thus, some materials are more desirable from the standpoint of economy in space, which is a major factor in the evacuation of small volume devices, such

as sub-miniature electron tubes, and the like, and from the further standpoint of economy in cost, which in respect to some material can be considerable where production is high. Further, some of the mentioned materials, including palladium, react reversibly with hydrogen, but do not react irreversibly or at a satisfactory rate with other active gases. These materials, while they may not be suitably adapted for evacuation of electric discharge devices or any other devices which require substantially high degrees of evacuation of all active gases, are satisfactory for the evacuation of other devices such as, for example, vacuum bottles or insulation panels which require a substantially high degree of evacuation but which are not substantially adversely affected by small residual quantities of active gases. Still further, some of the above-noted materials are currently less feasible commercially from the standpoints of costs and availability even though theoretically they are as equally suitable in carrying out the presently disclosed process as others.

Thus, it will be seen from the foregoing that the material to be selected from the above-noted group for the purpose of practicing the hydrogen furnace method of the present invention will be dependent largely on such factors, for example, as the type of device to be evacuated by means of the present method, the other materials used in the device and the size of such device as well as the temperatures and solder materials desired to be used and the commercial availability and cost of the selected material.

It will be further understood from the foregoing that while dry hydrogen has been found particularly suitable as the furnace atmosphere in evacuating electric discharge devices in the manner described above primarily owing to the fact that the activated oxide cathode would be adversely affected by moisture, the described method, broadly considered, requires only that the atmosphere supplied to the furnace be essentially hydrogen. That is, for the evacuation of some devices the described method may be practiced employing, for example, "forming gas" which is a commercially available gaseous admixture comprising approximately 8% to 20% nitrogen and the remainder hydrogen by volume. Of course, when using these gases it is necessary to select from the above-noted group a material which will react satisfactorily with both the hydrogen and elements comprising the other gaseous constituents and it is necessary to utilize a sufficient quantity of the material to sorb all of the elements required to be sorbed for satisfactory operation of the device. Additionally, it is necessary to select a sealing temperature at which the hydrogen-sorbing material will be best adapted for reacting with the gases entrapped in the device.

It will be appreciated from the foregoing that for the evacuation of some types of devices, such as those not adversely affected by the presence therein of oxygen, water vapor, or the like during processing, the method of the present invention can be practiced with the use of other than hydrogen or essentially hydrogen atmospheres.

As pointed out above, titanium, zirconium and the other above-mentioned materials are capable of reacting irreversibly with most active gases other than hydrogen. Thus, a device 15 including the above-described thermally operative sealing means or brazing material and a quantity of titanium, zirconium, etc. will, when heated, in an atmosphere, for example, of nitrogen, air, carbon monoxide, or carbon dioxide, first evolve occluded gases from the various materials of the device, then become filled with an expanded quantity or portion of the particular gas used, and then become sealed by the melting of the brazing material, thereby to entrap the mentioned expanded portion of gas. Both before and after sealing the gas-sorbing substance contained in the device will be effective for sorbing the active gases in the device, the active gases other than hydrogen being irreversibly sorbed at the elevated temperatures, and the hydrogen, if any, being

sorbed when the device subsequently cools. Thus, the device is both sealed and evacuated by one heating step; and where the envelope of the device is formed by conjoining component parts, the sealing and conjoining are accomplished by one and the same brazing operation, and are effected during the same heating step that renders the gas-sorbing material reactive with the entrapped gas. Inasmuch as the entrapped gas is thermally expanded, in effect, less gas is required to be sorbed than otherwise.

In order to effect the desired evacuation it is necessary to provide a sufficient quantity of titanium or other gas-sorbing material. This quantity can be equal to the molar equivalent of the quantity of gas to be sorbed. It is further necessary to control the brazing time to prevent saturation of the gas-sorbing material by the gas of the atmosphere before sealing which would render the material ineffective for sorbing gas and evacuating the device after sealing. This can be accomplished by rapidly heating the device and the gas-sorbing material to the desired elevated temperature.

When carbon dioxide is used as the furnace atmosphere barium oxide can be employed as the gas-sorbing material instead of the above-mentioned materials. The barium oxide will, at relatively low temperatures, react reversibly with the carbon dioxide to form barium carbonate and at higher temperatures will form carbon dioxide and barium oxide. Thus, when the above-described combined brazing, sealing and evacuating process is practiced using barium oxide as the gas-absorbing material it will give up carbon dioxide at the elevated temperature at which outgassing and brazing occur, and after sealing the material will sorb entrapped carbon dioxide, thereby to evacuate the device.

It will be further seen from the foregoing that the present invention could be carried out in the normal atmosphere, if the proposed uses of a device whose internal pressure has been reduced in this manner will tolerate the final pressures obtainable. That is, if the invention is practiced in the normal atmosphere it is possible to effect sealing, brazing together of component envelope parts and heat-cycling of the gas-sorbing material necessary to render it effective for sorbing the gas entrapped after sealing, all by means of a single heating step. However, because of the amounts of noble gases normally present in the atmosphere and which will not be sorbed, the final pressure in the device will be less than, for example, where a dry hydrogen atmosphere is utilized to sweep out the noble and other gases.

It will be still further understood from the foregoing that while the method of the present invention has been described as applicable for evacuating enveloped devices it is equally applicable to both the production of inert gas and hydrogen-filled or charged devices.

For example, where it is desirable to fill an electric discharge device or any other enveloped device with an inert gas, such, for example, as xenon, argon, krypton, or neon, the above-described method is employable simply by admixing with the essentially hydrogen furnace atmosphere a predetermined amount of the desired inert gas. Thus, when the device is sealed in the furnace it contains a quantity of inert gas along with an entrapped portion of the furnace atmosphere. Following sealing, the titanium, or other appropriate material selected from the above-mentioned group, effectively sorbs or combines with the gases in the device other than the inert gas in the manner described above, thus leaving the device evacuated of all the gases other than the inert gas or, in other words, filled or charged with the inert gas.

The degree of charging with the inert gas, is, of course, readily determinable or controllable by controlling the relative rates of inert gas and essentially-hydrogen gas admitted into the furnace and the sealing temperature. Alternatively, and, if desirable, the inert gas and essentially hydrogen gas can be admixed in predetermined quantities externally of the furnace and then fed thereto.

The method of the present invention is also applicable in obtaining a hydrogen-filled or charged device such, for example, as a hydrogen thyratron. When the method is used for this purpose it is practiced in substantially the same manner described above with regard to the evacuation of enveloped devices, except that the quantity of titanium or other material used is not such as to sorb all the residual hydrogen following sorption of the other active gases and upon cooling of the device. Instead, an amount of material is employed which will sorb hydrogen upon cooling only to the extent of bringing the pressure thereof down to a predetermined desired final or operating pressure. This amount of gas-sorbing material is determined preferably experimentally in connection with the particular tube structure and its contents because of varying conditions and tube materials and the effects thereof on gas clean-up, surface sorption and solubility of the gas in the electrodes of the device.

The present invention also contemplates a method and structure for maintaining the above-mentioned predetermined desired operating pressure during the life of a hydrogen-charged device.

A structure adapted for accomplishing this is illustrated in Figure 4. This structure is similar to that shown in Figure 1 and identical numerals designate elements which are identical in construction and purpose to those provided in the device of Figure 1. The device of Figure 4 differs from that of Figure 1 in that it comprises an envelope 56 including an additional ceramic section 57 and conductive frusto-conical support member 58. The support member 58 is provided with a rim 59 and an upturned lip portion 60 adapted for engaging the lower peripheral surface of the ceramic section 57 and being sealed thereto and to the other adjacent elements of the envelope structure in the same manner as that described above with respect to the device of Figure 1.

The member 58 is re-entrant in the sleeve 57 and carries on the upper internal surface thereof one of the aforementioned disks 50 formed of a material selected from the above-noted group of materials characterized by their proclivity to sorb substantial quantities of hydrogen at reduced temperatures. Alloying of the material of the member 50 to the supporting surface of the member 58 is avoided by an interposed layer of molybdenum 51.

Also supported by the member 58 and disposed on the side thereof opposite the disk 50 is a heating element 60. One side of the heating element is electrically connected to the member 58 and the other side is connected to one leg of the cathode filament 44 which extends through suitable apertures in the members 50, 51 and 58 and is electrically connected to the member 45.

During the processing of the device the material of the disk 50 sorbs hydrogen in the manner described above. Subsequently, during the normal operating life of the tube there is a tendency for the internal pressure of the device to decrease. When this occurs the internal pressure can be increased by energizing the heating element 60 which raises the temperature of the disk 50, thereby to desorb hydrogen therefrom for replenishing the charge of the device. It will be seen that the amount of hydrogen thus released from the disk can be controlled by controlling the energization of the heater 60.

While we have shown and described specific embodiments of our invention we do not desire our invention to be limited to the particular form shown and described and we intend by the appended claims to cover all modifications within the spirit and scope of our invention.

What we claim as new and desire to secure by Letters

Patent of the United States is:

1. The method of sealing and evacuating an envelope comprising the steps of providing an envelope with an opening, disposing a thermally operative sealing means in said opening, placing said envelope in an enclosure, supplying a predetermined active gas to said enclosure substantially to displace the normal atmosphere

of said envelope, heating said envelope to a predetermined temperature range wherein said sealing means is rendered effective for sealing said envelope and entrapping therein a thermally expanded portion of said gas, and including in said envelope a quantity of substance capable of sorbing a substantial quantity of the entrapped portion of said gas both while in said predetermined temperature range and upon subsequent cooling.

2. The method of sealing and evacuating an envelope comprising the steps of providing an envelope with an opening, disposing a thermally operative sealing means in said opening, displacing the normal gaseous contents of said envelope with a thermally expanded quantity of a predetermined active gas, including in said envelope a quantity of a substance which is capable of desorbing said gas upon heating and sorbing said gas upon cooling, elevating the temperature of said substance and said sealing means for effecting desorption of substantially all previously sorbed gas from said substance and then rendering said thermally operative sealing means effective for sealing said envelope to entrap a quantity of said gas therein, and permitting said substance to cool for effecting sorption thereby of the gas entrapped in said envelope.

3. The method of manufacturing an envelope having predetermined internal pressure conditions comprising the steps of substantially displacing the normal gaseous contents of said envelope with a heated and thereby substantially rarified atmosphere comprising essentially hydrogen, including in said envelope a quantity of hydrogen-sorbing material which is reversibly reactionable with hydrogen, elevating the temperature of said material to desorb substantially all previously sorbed hydrogen while said envelope is open, sealing said envelope and thereby entrapping a quantity of said rarified atmosphere therein while the temperature of said material is elevated, and permitting said material to cool for effecting sorption thereby of a predetermined quantity of the hydrogen entrapped in said envelope.

4. The method of manufacturing an envelope having predetermined internal pressure conditions comprising the steps of including in said envelope a predetermined quantity of material which is reversibly reactionable with hydrogen and irreversibly reactionable with other active gases, heating said envelope including said material while said envelope is open to an essentially hydrogen atmosphere and to a predetermined elevated temperature range wherein substantially all previously sorbed hydrogen is desorbed by said material and other active gases in said envelope are sorbed by said material, sealing said envelope while in said predetermined elevated temperature range, whereby a substantially rarified quantity of hydrogen is entrapped in said envelope, and cooling said material for effecting sorption thereby of a predetermined quantity of the hydrogen entrapped in said envelope.

5. The method of evacuating an envelope comprising the steps of including in said envelope a quantity of substance comprising material selected from the group including titanium, zirconium, cerium, thorium, hafnium, lanthanum, neodymium, praseodymium, vanadium, tantalum, columbium, palladium and the hydrides thereof, heating said envelope and its contents including said substance for evolving gases therefrom, displacing the gaseous contents of said envelope with an atmosphere comprising essentially hydrogen, sealing said atmosphere in said envelope, and reducing the temperature of said substance for effecting sorption thereby of the hydrogen in said atmosphere.

6. The method of evacuating an envelope comprising the steps of including in said envelope a predetermined quantity of substance comprising material selected from the group including titanium, zirconium, cerium, thorium, hafnium, lanthanum, neodymium, praseodymium, vanadium, tantalum, columbium and the hydrides thereof, heating said envelope opened in a flushing atmosphere

comprising essentially hydrogen, whereby the gaseous contents of said envelope are substantially replaced by a rarefied quantity of said atmosphere, heating said substance to a predetermined temperature range wherein substantially all hydrogen is desorbed by said material and said material is adapted for sorbing active gases in said envelope other than hydrogen, sealing said envelope in said temperature range, and reducing the temperature of said substance for effecting sorption thereby of the hydrogen sealed in said envelope.

7. The method of fabricating and evacuating an envelope comprising the steps of providing a structure including a plurality of members adapted for being joined to form a sealed envelope, including in said structure a quantity of substance comprising material selected from the group including titanium, zirconium, cerium, thorium, hafnium, lanthanum, neodymium, praseodymium, vanadium, tantalum, columbium, palladium and the hydrides thereof, providing a thermally operable bonding material between said members, substantially displacing the gaseous contents of said structure with an essentially hydrogen atmosphere, heating said structure and substance for rendering said bonding material effective to join said members and thereby complete a sealed envelope and for adapting said substance to sorb the residual hydrogen upon cooling, thereby to evacuate said envelope, and cooling said structure and substance.

8. The method of sealing and evacuating an envelope comprising the steps of providing an envelope with an opening, including in said envelope a quantity of substance comprising material selected from the group including titanium, zirconium, cerium, thorium, hafnium, lanthanum, neodymium, praseodymium, vanadium, tantalum, columbium and the hydrides thereof, disposing in said opening a brazing material adapted for flowing in a predetermined temperature range wherein said substance is adapted for desorbing substantially all previously sorbed hydrogen and sorbing active gases other than hydrogen, substantially displacing the gaseous contents of said envelope with an atmosphere comprising essentially hydrogen, heating said envelope and contents to said predetermined temperature range, whereby active gases in said envelope other than hydrogen are sorbed by said substance and said brazing material flows for sealing said envelope, and reducing said temperature, whereby said brazing material is solidified and said substance is adapted for sorbing the hydrogen sealed in said envelope.

9. The method of sealing and evacuating an envelope including the steps of providing an envelope with an opening, including in said envelope a quantity of substance comprising material selected from the group including titanium, zirconium, cerium, thorium, hafnium, lanthanum, neodymium, praseodymium, vanadium, tantalum, columbium and the hydrides thereof, disposing in said opening a brazing material adapted for flowing in a predetermined temperature range wherein said substance is adapted for sorbing active gases other than hydrogen, heating said envelope and its contents to said predetermined range in a continuously refreshed dry hydrogen atmosphere, whereby gases are evolved therefrom, the gaseous contents of said envelope are substantially replaced by a rarefied essentially hydrogen atmosphere, active gases in said envelope other than hydrogen are sorbed by said substance and said brazing material is caused to flow for sealing said envelope, and reducing said temperature, whereby said brazing material is solidified and said substance is rendered effective for sorbing substantially all the hydrogen sealed in said envelope.

10. The method of manufacturing an electric discharge device comprising the steps of mounting in an open envelope an electrode assembly including a cathode comprising material requiring activation, including in said envelope a substance comprising material selected from

the group including titanium, zirconium, and the hydrides thereof and at least sufficient in quantity for sorbing a quantity of hydrogen corresponding generally to the volume of said envelope, heating the material of said cathode to effect activation thereof, substantially displacing the gaseous contents of said envelope with an essentially hydrogen atmosphere, heating said substance to a temperature range wherein it releases previously sorbed hydrogen and sorbs active gases in said envelope other than hydrogen, sealing said envelope in said temperature range, and cooling said substance for sorbing the hydrogen sealed in said envelope, thereby to evacuate said device.

11. The method of manufacturing an electric discharge device comprising the steps of mounting in an open envelope an electrode assembly including a cathode requiring chemical reduction for activation, including in said envelope a substance comprising materials selected from the group including titanium, zirconium and the hydrides thereof and at least sufficient in quantity for sorbing a quantity of hydrogen corresponding generally to the volume of said envelope, chemically reducing said cathode, heating said envelope and its contents in an essentially hydrogen atmosphere, thereby to evolve gases therefrom and replace the gaseous contents of said envelope with a rarefied quantity of said hydrogen atmosphere, heating said substance to a predetermined temperature range wherein said substance releases any previously sorbed hydrogen and sorbs residual active gases in said envelope other than hydrogen, sealing said envelope in said predetermined temperature range, and cooling said substance for sorbing the hydrogen sealed in said envelope, thereby to evacuate said device.

12. The method of manufacturing an electric discharge device comprising the steps of providing a structure including a plurality of insulative and conductive members adapted for being joined by brazing to form a sealed envelope, providing brazing material between said members, mounting in said structure an electrode assembly including a cathode comprising materials requiring chemical reduction for activation, including in said structure a quantity of substance comprising material selected from the group including titanium, zirconium and the hydrides thereof and at least sufficient in quantity for sorbing a quantity of hydrogen corresponding generally to the volume of said structure, chemically reducing said cathode, heating said structure and its contents in a dry hydrogen atmosphere, thereby to evolve gases therefrom and replace the gaseous contents of said structure with a rarefied quantity of said hydrogen, heating said structure and substance to a predetermined temperature range wherein said brazing material is caused to flow for joining said members to effect a sealed envelope and wherein said substance releases any previously sorbed hydrogen and sorbs residual active gases in said envelope other than hydrogen, and cooling said substance for sorbing the hydrogen sealed in said envelope, thereby to evacuate said device.

13. The method of manufacturing an inert gas charged enveloped device comprising the steps of including in said device a quantity of substance comprising materials selected from the group including titanium, zirconium, cerium, thorium, hafnium, lanthanum, neodymium, praseodymium, vanadium, tantalum, columbium, palladium and the hydrides thereof, substantially displac-

ing the gaseous contents of said device with an atmosphere comprising essentially hydrogen and an inert gas, sealing said atmosphere in said device, and heating said substance for effecting sorption upon cooling of said hydrogen, thereby to leave said device charged with said inert gas.

14. The method of manufacturing an inert gas charged enveloped device comprising the steps of including in said device a quantity of material selected from the group including titanium, zirconium, cerium, thorium, hafnium, lanthanum, neodymium, praseodymium, vanadium, tantalum, columbium, and the hydrides thereof, heating said device opened in a dry hydrogen atmosphere containing a predetermined quantity of an inert gas, thereby to evolve gases from the materials of said device and to effect displacement of the gaseous contents thereof with an atmosphere comprising essentially hydrogen and said inert gas, heating said substance to a predetermined temperature range wherein active gases in said device other than hydrogen are sorbed by said substance, sealing said device, and reducing the temperature of said substance for effecting sorption thereby of the hydrogen sealed in said device and thus leaving said device charged with a predetermined quantity of said inert gas.

15. The method of manufacturing a hydrogen charged envelope and determining the internal pressure thereof comprising the steps of including in said envelope a quantity of substance selected from the group including titanium, zirconium, cerium, thorium, hafnium, lanthanum, neodymium, praseodymium, vanadium, tantalum, columbium, palladium and the hydrides thereof and sufficient in quantity to sorb a quantity of hydrogen less than the volume of said envelope, heating said envelope open in a hydrogen atmosphere, thereby substantially to displace the gaseous contents of said envelope with a hydrogen atmosphere, said heating adapting said substance for effecting sorption thereby upon cooling of only a predetermined quantity of said hydrogen for thus leaving said envelope hydrogen charged to a predetermined degree, and subsequently reheating said substance to a predetermined extent for increasing the hydrogen charge in said envelope.

16. The method of manufacturing an envelope having predetermined internal pressure conditions comprising the steps of including in said envelope a predetermined quantity of a substance comprising approximately 50 percent each of titanium and zirconium, substantially displacing the gaseous contents of said envelope with an atmosphere comprising essentially hydrogen, and heating said substance for effecting sorption thereby upon cooling of a predetermined quantity of said hydrogen over a substantial temperature range.
